D 18226

Design No. 18,226, dated April 3, 1868.

FIG. 1.

FIG. 2.

UNITED STATES PATENT OFFICE.

FRANCIS A. COFFIN, OF INDIANAPOLIS, INDIANA.

DESIGN FOR A WRITING-DESK.

SPECIFICATION forming part of Design No. 18,226, dated April 3, 1888.

Application filed December 15, 1887. Serial No. 258,034. Term of patent 7 years.

To all whom it may concern:

Be it known that I, FRANCIS A. COFFIN, of Indianapolis, county of Marion and State of Indiana, have invented a certain new and original Design for Writing-Desks; and I do hereby declare that the following is a full, clear, and exact description thereof, reference being had to the accompanying engravings, which illustrate the same.

10 In the engravings, Figure 1 represents a perspective view of my newly-designed desk, all the openings being closed up. Fig. 2 is a similar view of the same, the desk-curtain being rolled back and the door of the cabinet being open, showing the interior arrangement.

15 The desk itself belongs to that class known as "cabinet-desks," and it consists of a table supported upon pedestals, in one of which is a series of drawers of different widths, and in 20 the other a single drawer, below which is a cupboard having partitions and closed by a door, and between these two divisions of the desk is an open central space. Upon the top is fixed a cabinet portion inclosing a series 25 of partitions and a couple of small drawers, with an open space between and below them. The top is closed by a flexible curtain, in the usual manner. The edges of the sides of the top and of the table portion are molded, as 30 shown. The pedestals of the desk are separated by flat pilasters having molded bases and capitals. The fronts of the drawers project beyond the face of the frame-work and have beveled edges. Plain straight handles 35 with beveled edges and rounded ends are secured thereto, as shown. The small drawers in the cabinet also have handles, and above and below them their fronts are finished with

plain straight lines, as is also the central piece below the table between the pedestals of the 40 desk. The sides of the desk are paneled, the side of the top portion being of a single panel and the body portion of double panels. The escutcheon for the key-hole is fixed upon a rectangular-shaped piece, as shown.

45 The leading features of my design consist in the molded edges of the table and top portions, the front composed of a series of drawers on one side, a single drawer and book cupboard upon the other, the front corners of the 50 pedestals ornamented with flat molded pilasters with molded bases and capitals, the drawers having beveled edges, and the general design of the whole, as herein described.

55 I claim—

The design for a desk herein shown and described, consisting of a pair of pedestals supporting a cabinet-top of medium height, the one pedestal containing a series of drawers increasing in width from top to bottom, the other 60 a single drawer and a cupboard provided with partitions, the drawer-fronts having plain beveled edges and handles with flat tops and rounded ends, their edges also beveled, the front corners of the pedestals ornamented with 65 flat pilasters having molded bases and capitals, and drawers upon the inside of the cabinet, having handles similar to those in the pedestals, their fronts ornamented with straight lines above and below the handles.

70 In witness whereof I have hereunto set my hand this 2d day of November, 1887.

FRANCIS A. COFFIN.

Witnesses:

C. P. JACOBS,
E. B. GRIFFITH.
